UNITED STATES PATENT OFFICE.

JAMES McMAHON, OF NEW YORK, N. Y.

SUPPORT FOR MASONRY ARCHES AND THE LIKE.

1,055,345.

Specification of Letters Patent. Patented Mar. 11, 1913.

Application filed August 30, 1911. Serial No. 646,854.

To all whom it may concern:

Be it known that I, JAMES McMAHON, a subject of the King of Great Britain, residing in the borough of Brooklyn, county of 5 Kings, city and State of New York, have invented certain new and useful Improvements in Supports for Masonry Arches and the Like, of which the following is a specification.

10 My invention relates to an improved support for masonry arches, floors, ceilings and like structures.

In building construction it is customary to provide a temporary support of beams or 15 scaffolding upon which the arch floor or the like of brick or hollow tile is laid, and when the brick or tile have set the support is removed, leaving the complete arch or floor in position with its ends taking into 20 the I-beams or iron girders at the sides of the room. Difficulty has heretofore been experienced in safely anchoring the scaffolding and providing suitable means for removing the same after the need therefor 25 is past, and the primary object of my invention is to provide a simple, strong and inexpensive support for the beams or scaffolding, which support may be readily anchored in position, and after the arch or 30 floor has set may be removed, permitting the scaffolding to fall and the arch to remain in position.

The invention is illustratively exemplified in the accompanying drawing, wherein— 35 Figure 1 is a plan view of a skeleton iron structure adapted to receive an arch or floor of brick or concrete, a plurality of my improved supports being shown in position; Fig. 2 is a horizontal sectional view taken 40 on the line 2—2 of Fig. 1; and Fig. 3 is a vertical sectional view taken on the line 3—3 of Fig. 2.

Stated in general terms, the invention includes a vertically adjustable supporting 45 arm for the scaffolding or the like and means for supporting said arm from a firm part of the building in course of construction.

Stated in more specific terms, the invention 50 embodies an elongated, preferably cylindrical rod or bar on which the supporting arm for the scaffolding is longitudinally adjustable, there being also a plate movable on the bar and having a hook end adapted 55 to engage the flange of an I-beam or girder

to hold the device firmly in suspended position.

Referring to the accompanying drawing, and particularly to Figs. 2 and 3 thereof, 10 designates a rod or bar, preferably cylindrical in form, and screw threaded near one end 10^a to receive a correspondingly internally threaded hand hold or handle 11. Adapted to be arranged below the handle 11 is an anchorage plate 12 having the hooked end 13, the plate being adapted to take over the flange of the I-beam 14 as shown in Fig. 2 and hold the device firmly in suspended position. Near its opposite end the rod 10 is provided with a plurality of orifices 15 of 15 a size to accommodate a cross-key or pin 16 such as shown in the uppermost of the series of orifices. The cross-key has an enlarged head 16^a to prevent its slipping through the orifices, and when the key is inserted in one of the orifices it projects at either side of the rod 10 and forms a stop for a bearing or supporting arm 17 having upturned ends 17^a and adapted to support the scaffolding upon which the hollow tile 20 or brickwork is built. As shown in Fig. 2 of the drawing the arm 17 is really in the nature of a double arm, the two branches thereof being connected by a boss 17^b having formed therein an annular opening 17^c 25 which connects with lateral elongated slots 17^d. In the form of device shown in Fig. 1, there is but a single supporting arm 17 for each device. It will, of course, be understood that my invention contemplates the 30 provision of either a single arm 17 or a double arm, as the case may require.

The manner of using the invention is shown in Fig. 1. A series of the improved supporting devices are hung, by means of 35 the plates 12, to the flanges of the I-beams 14. There is then laid across the supporting arms 17 timbers 18 which serve to support the cross timbers 19, these two sets of timbers forming a scaffolding on which the 40 hollow tile or brick work is built across the room and into the space between the flanges of the I-beams. After the tile or brick has set the scaffolding is removed, and this may be done either by knocking the pins 16 out 45 of the orifices 15 or by turning the rod 10 about its axis until the projecting ends of the pin align with the slots 17^d, so that in either event the arm 17 may slide down the 50 rod and permit the scaffolding to drop. To 55

enable the rod to be turned, it is provided at its upper end with an orifice 15^a to receive a suitable tool that may be used to turn the rod. After the arm 17 has been removed, 5 the handle 11 is turned on the thread 10^a until the rod 10 drops out of the handle; then the plate 12 is removed from the flange of the I-beam, and the several parts of the device may then be reassembled and 10 stalled for use in another place.

It will be understood that the purpose of the plurality of orifices 15 is to provide means for adjusting the arm 17 vertically so as to accommodate different thicknesses 15 of scaffolding and varying thicknesses of brick or tile floors or arches. The handle 11 is provided to lower or raise the rod 10 into such position that the arm 17 when loaded always stand straight, horizontally.

20 Having thus described my invention what I claim as new and desire to secure by Letters Patent is:—

In a device of the character described, the

combination with a hooked plate adapted to take over a fixed support, of a rod movable 20 in said plate, means whereby said rod may be raised and lowered in said plate, said rod having a plurality of perforations near one end thereof, a supporting arm independent of and slidable on said rod, said 30 arm having therein a substantially annular opening and connecting lateral slots, the annular opening in said arm being adapted to engage said rod whereby said arm is revoluble about and longitudinally movable 35 on said rod, said supporting arm having oppositely disposed upturned ends and a pin adapted to be inserted in said perforations to hold said arm in adjusted position on said rod.

In testimony whereof I have affixed my signature in presence of two witnesses.

JAMES McMAHON.
